LET-BACK MECHANISM FOR LOOM LET-OFFS

Filed Sept. 21, 1925

Patented Feb. 8, 1927.

UNITED STATES PATENT OFFICE.

KENNETH J. UNWIN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LET-BACK MECHANISM FOR LOOM LET-OFFS.

Application filed September 21, 1925. Serial No. 57,489.

This invention relates to let-offs for looms and more particularly to let-back mechanisms by means of which the warp and cloth may be moved rearwardly at the time of a pick out. It not infrequently happens that a mispick will not be detected until a number of picks after it occurred and the weaver is required to unweave back to the mispick to remove the latter. This process is accomplished by taking out the picks laid subsequent to the mispick, after which it is necessary to move the fell of the cloth back to the position the reed occupies when on front center. It is desirable that in this reverse motion the yarn be placed under the same tension as existed before the pick out and it is further desirable that the friction devices which normally retard the movement of the warp beam or drum be adjustable from the front of the loom. It is accordingly the principal object of my invention to provide an improved adjustment for friction let-offs accessible from the front of the loom and so arranged as to permit a reversal of the warp while keeping the same under the same tension which exists under ordinary weaving conditions.

It is a still further object of my invention to employ the usual type of adjustment rendering the same positive in both directions and making it possible to detach the same from its normal position so that the friction may be temporarily increased or decreased at the will of the operator.

It is a still further object of my invention to provide a flexible friction band of fixed length to cooperate with a two-part friction drum the position of which is varied by means of a wedge controlled from the usual handle extending toward the front of the loom.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a vertical longitudinal section through a loom having my invention applied thereto,

Fig. 2 is an enlarged vertical section on line 2-2 of Fig. 1,

Fig. 3 is a vertical section on line 3-3 of Fig. 2,

Fig. 4 is a fragmentary horizontal section on line 4-4 of Fig. 3,

Fig. 5 is a top plan view of the wedge looking in the direction of arrow 5, Fig. 2,

Fig. 6 is a section on line 6-6 of Fig. 5 and

Fig. 7 is an enlarged vertical section on line 7-7 of Fig. 1.

My invention is usable on various types of looms but is applicable more particularly to duck looms where the warp may be derived either from a warp beam mounted directly on the loom frame or from a creel disposed rearwardly of the loom and having associated therewith a warp drum around which the warp threads extend when passing from the creel to the harness mechanism. I have chosen to illustrate my invention in connection with a warp delivery drum such as is used with creels but it is to be understood that I am not limited to this particular mode of employing my invention.

Referring to the drawings it will be seen that I have provided a loom frame 10 on which is mounted a warp delivery drum 11 around which the warp threads W extend before passing to the harness mechanism not shown. Rigid with said drum 11 is a gear 12 which meshes with a pinion 13 keyed to the hub 14 of bracket 15 which is loosely mounted on a shaft 16.

Said bracket is provided with a pair of arms 17 and 18, respectively, see Fig. 3, to which are secured the ends of a flexible friction band 19 by means of bolts 20. The band 19 is thus required to move with the pinion 13 and the warp drum 11. An expandible drum engages the interior of the friction band 19 and is formed of two pivotally connected parts 21 and 22, respectively, the latter part being provided with ears 23 between which extends a pin 24. A lever 25 is loosely mounted on the pin between the ears and has an arm 26 which is pressed against the drum section 21. The degree of friction existing between the drum sections and the flexible band 19 is determined by the position of the lever 25.

In order to move said lever 25 angularly about the pivot thereof I provide a collar 27 loosely mounted on the shaft 16 and

having a slabbed hub 28. The outer end of the shaft 16 is supported by a bearing 29 and in order to vary the longitudinal position of collar 27 I provide a forked wedge 30 between said collar and the bearing 29. The slabbed hub of the collar extends between the tines of the wedge and prevents rotation of said collar. As the wedge is moved transversely with respect to the collar the latter is moved correspondingly toward or from the lever 25 to affect the position thereof.

Said wedge is secured to rod 31 which is adjustably connected at the forward end thereof to a hand lever 32 pivoted as at 33 to the loom frame. The forward end of the lever has a portion extending between the upper and lower arms 34 and 35, respectively, of a threaded block 36 mounted on a screw 37 and can be flexed into and out of the notch defined by said arms. Said screw is rotatable in bearings 38 formed on a bracket 39 secured to the loom frame and is held against longitudinal motion by a hand wheel 40 on the upper side of the upper bearing 38 and a collar 41 fixed to the screw of the under side of the upper bearing. The rear face of the block 36 engages the adjacent wall of the bracket and is thereby held against rotation as the screw is turned. The matter thus far described relates to the mechanism for adjusting the friction between the band 19 and the drum sections 21 and 22.

As previously stated it is desirable to reverse the direction of the warp drum and this is accomplished by mechanism controllable from the front of the loom. Said mechanism comprises a worm gear 42 keyed to the shaft 16 and meshing with the worm 43 fastened to the rear end of an inclined shaft 44 which is received by bearings 45 secured to the loom frame. A hand wheel 46 affords means for turning the shaft 44. This mechanism provides a ready means for reversing the warp drum 11 through the friction devices previously described. Resilient means 47 are connected to the drum sections 21 and 22 to move the same together when the lever 25 is moved to relieve the friction.

Under normal conditions the drum 11 will rotate and cause the flexible band 19 to move around the friction surface of the drum sections 21 and 22. Said drum sections are pivoted together as at 48 and the section 22 is keyed to the shaft 16 as at 49. Inasmuch as worm gear 42 is held against angular motion by worm 43 and is keyed to shaft 16, the sections 21 and 22 will also be held against rotation as the leather band 19 moves with the warp drum 11. If it be desired to adjust the friction the screw 37 may be rotated in the proper direction either to move the collar 27 toward or from the lever 25 according to whether the friction is to be increased or decreased.

At the time of pick out when the picks which were laid after the mispick occurred have been removed, the hand wheel 46 is turned to give a reverse movement to the drum sections 21 and 22 through the worm 43 and gear 42. This will cause the flexible band 19 to move with said sections and will in turn rotate the pinion 13, gear 12 and warp drum 11. After the fell of the cloth has reached the reed when the latter is on front center the hand wheel 46 can be rotated a little farther to cause slipping between the drum sections 21 and 22 and the flexible band 19, this latter procedure insuring that the warp and cloth are under the same tension which existed before the pick out.

From the foregoing it will be seen that I have provided a let-back mechanism for loom let-offs having a wedge actuatable from the front of the loom for controlling the friction and that the latter can be reversed to exert the same turning force on the warp drum in a reverse direction as resists normal forward movement of said drum. Also, the lever 32 can be flexed away from the block 36 to enable the weaver to increase or decrease the friction temporarily without disturbing the setting of said block.

Having thus described my invention it will be apparent that changes and modifications may be made therein by those skilled in the art without departing from the spirit and scope of the invention, and I do not wish to be limited to the details herein disclosed but what I claim is:

1. In a let-off mechanism for looms having a warp delivery means and a friction surface movable therewith, an expandible friction element to cooperate with the friction means to retard movement of the warp delivery means, a rotatable screw at the front of the loom, a wedge to control the expandible element, and connections from the screw to the wedge to move the latter positively in opposite directions.

2. In a let-off mechanism for looms having a warp delivery means and a friction surface movable therewith, an expandible friction element cooperating with the friction surface to retard movement of the warp delivery means, means to expand the element including a lever in contact with a portion thereof and a wedge to position the lever, and means to move the wedge positively in opposite directions and hold the same in any position thereof.

3. In a let-off mechanism for looms having a warp delivery means and a friction surface movable therewith, an expandible friction element cooperating with the friction surface to retard movement of the warp delivery means, means to expand the element including a lever in contact with a portion thereof and a wedge to position the

lever, and means to move the wedge positively in opposite directions and hold the same in any position thereof, said means including a screw mounted for rotation near the front of the loom.

4. In a let-off mechanism for looms having a warp delivery means and a friction surface movable therewith, an expandible friction element cooperating with the friction surface to retard movement of the warp delivery means, a lever to expand the element, a wedge to move the lever, a lever to position the wedge, a screw mounted at the front of the loom for rotation, and positive connections between the screw and the second named lever to move the latter and the wedge in two directions by rotating the screw.

5. In a let-off mechanism for looms having a warp delivery means and a friction

surface movable therewith, an expandible friction element to cooperate with the friction surface to retard movement of the warp delivery means, a wedge movable in opposite directions, connections between the wedge and the element to vary the degree of expansion of said element, a lever to position the wedge having an arm capable of being flexed laterally, a screw mounted for rotation at the front of the loom, a block 30 mounted on the screw and movable therewith by rotation of the screw, and a pair of spaced ears on said block between which the arm of the lever is normally positioned, the said arm being movable laterally out of 35 alignment with the ears to position the wedge independently of the screw.

In testimony whereof I have hereunto affixed my signature.

KENNETH J. UNWIN.
